UNITED STATES PATENT OFFICE.

CHESTER A. VAN DEMARK; OF KINGSTON, NEW YORK.

MATTRESS-HOLDER.

1,336,003.

Specification of Letters Patent.

Patented Apr. 6, 1920.

Application filed September 25, 1919. Serial No. 326,356.

To all whom it may concern:

Be it known that I, CHESTER A. VAN DEMARK, a citizen of the United States, residing at Kingston, in the county of Ulster and State of New York, have invented certain new and useful Improvements in Mattress-Holders, of which the following is a specification.

This invention relates to certain new and useful improvements in beds and comprises 10 a mattress holder arranged to be attached to an iron frame bed spring.

The primary object of this invention is to provide conventionally constructed metal frame bed springs with readily attachable and detachable members of the spring frame, with ease, accuracy and despatch, in a manner insuring the mattress being held 15 in proper position on the springs, and thereby insuring the mattress holding its shape.

With these and other ends in view which will readily appear as the nature of the invention is better understood, the same consists in the improved construction and 20 novel arrangement and combination of parts which will be hereinafter fully described and particularly pointed out in the claim.

In the accompanying drawings has been 25 illustrated a simple and preferred form of the invention, it being, however, understood that no limitation is necessarily made to the precise structural details therein exhibited, but that changes, alterations and modifications within the scope of the claim may be 30 resorted to when desired.

In the drawing:

Figure 1 shows a view partly in perspective of a bed equipped with my invention.

Fig. 2 is a side view of bed springs having 40 one of my holders attached thereto.

Fig. 3 is a modification.

Fig. 4 shows a detail of the attachment disclosing one of the brackets in perspective.

My invention is a bed spring mattress 45 protector and will keep the mattress in place at both head and foot of the bed and will also keep the mattress from stretching out of shape as it does on beds without this protector, as well as holding the mattress 50 against casual displacement.

In carrying out the object of my invention I employ a panel 8, of wood, or other suitable material arranged to be held parallel to the ends of the spring frame, and above 55 the same with its lower edge resting on said

frame, in the manner shown in Figs. 1 and 3 of the drawings.

Holding the panel in position at each end, are two metal brackets each including a flat securing end 6, from which extends at a right angle, a U-shaped spring member 5, from which is continued at a right angle in a direction opposite to the end 6, the holding end 7, having suitable openings to hold the screws 9 by means of which the panel is held 60 to the brackets.

The securing ends 6 have openings 10 through which pass suitable bolts 10' by means of which the brackets are held to the frame bar 3.

In certain cases I find that the horizontal flange 3 of the spring holding frame head 1, is of such a size that the U-shaped portion of the brackets can be sprung on the horizontal flange 3 of the frame bars as shown in 75 Fig. 3. Where this arrangement is possible no bolts are necessary to hold the bracket in position.

In the drawing I have shown at 1, the usual socket to receive the tubular members 2, while shown as secured to the bar 3 is the spring 4, the mattress 11, being clearly indicated.

Fig. 1, shows how the bed spring end looks when the protector is on the spring. 85 It is not clumsy or does not bother one when sleeping. It does not tear the sheets and is very easy to put on or take off any time. It is made to fit any kind of spring that has an iron frame around it, or any size spring. 90

From the foregoing description, taken in connection with the accompanying drawings, the operation and advantages of my invention will readily be understood.

I have entered into a somewhat detailed 95 description of the present and preferred embodiment of my invention in order to impart a definite understanding of the same. I do not desire, however, to be understood as restricting myself to the exact construction shown and described, as various changes or modifications may be made in the form, size, and minor details of construction without departing from the principle or sacrificing any of the advantages of this invention.

Having thus described my invention, what I claim, and desire to secure by Letters Patent, is:

In combination with the angle iron mat- 110

tress frame of a bed, of a bracket comprising a flat securing end from which extends at a right angle a U-shaped spring member arranged to be clasped over the 5 horizontal portion of said angle iron frame member, a holding end being continued from said spring member in a direction op-

posite to said securing end and a panel held to said holding end the lower edge of said panel resting on said angle iron frame, all 10 as and for the purpose set forth.

In testimony whereof I affix my signature.

CHESTER A. VAN DEMARK.
